BOLT LOCK

Joseph R. Griffith, Lynwood, Calif.

Application May 5, 1955, Serial No. 506,289

8 Claims. (Cl. 292—148)

Generally speaking, the present invention relates to the latch and lock arts and, more particularly, pertains to a bolt lock attachable to a door, cooperable with a padlock to lock said door to a jamb, and selectively unlockable from one side of said door and relockable from the other side of said door independently of said padlock.

It is an object of the present invention to provide a bolt lock adapted to cooperate with a padlock to effectively lock a door from a first side thereof and serve as a manually openable latch from a second side thereof.

It is also my object to provide a bolt lock, of the sort described in the preceding object, which is of an especially simple, rugged, effective and novel construction, especially suited for use on heavy exterior doors.

Other and allied objects of the present invention will occur to those skilled in the art after a careful study of the present specification, the accompanying illustrations, and the appended claims.

To facilitate understanding, reference will be made to the hereinbelow-described drawings, in which:

Fig. 1 is a perspective view of a preferred embodiment of the bolt lock of the present invention, locked with a padlock and with bolt means in extended, locked position; the padlock and certain invisible elements are indicated by dashed lines;

Fig. 2 is a perspective view of the device of Fig. 1 after it has had the bolt means unlocked from the inside (second side)—the parts shown solidly have moved from the positions they occupied in Fig. 1, all stationary parts being indicated by dashed lines;

Fig. 3 is a perspective view of the device of Fig. 1 after it has been unlocked, by removing the padlock, from the outside (first side), only parts which have been moved from the positions of Fig. 1 being shown solidly;

Fig. 4 shows a section through the device of Fig. 1, taken along the plane, and in the direction, indicated by the line and arrows 4—4 of Fig. 2; a second position of the handle and control means is shown in dashed lines;

Fig. 5 is an elevation of the device of Fig. 1 as seen, installed in a door, from the second side thereof; and

Fig. 6 shows a section, from the position shown in Fig. 4, of an embodiment of the present invention in which the control means is of different construction from that shown in Figs. 1—4; parts similar to those of the device of Figs. 1—4 are numbered similarly, but with primed numerals.

In the bolt lock illustrated in Figs. 1—4, the body means is a semi-cylindrical shell with closed ends, as indicated at 1. The open diametral plane of the body means is in use against the surface of the first side (left side in the figures) of a door A in which an aperture B has been provided as shown in Fig. 4. The body means has mounting flanges 2 which connect it to the door through the use of rivets or bolts (not shown) of a type non-removable from the first side and cooperable with mounting holes 3. On a portion 4 of the lower mounting flange—this portion 4 may be mounted separately on the door if

desired—staple 5 is held. A padlock C is linked through it in Figs. 1 and 2 to lock hasp 6 (whose aperture fits over the staple) on the staple. Hasp 6 passes through a slot 7 in the semicylindrical shell 1. Through an aperture 8 in the first end 1a of the shell 1, passes longitudinally slideable bolt 9, which is rotatable about its longitudinal axis. To lock the door the bolt end engages a bolt receptacle on a door jamb, which structures are well-known in the art and hence are deemed not to require illustration. Projecting from bolt 9 are pin 10, handle 11 which extends through aperture B to the second side of door A, and flange 12. A collar portion 6b of hasp 6 is slideable along the bolt 9 and defines an aperture whose ends are engageable by pin 10. The aperture B in the door is virtually rectangular; its length should allow the travel of handle 11 from the position of Fig. 1 to the position of Fig. 2 or Fig. 3. As shown in Fig. 4, on the left side the wood of the door is further cut away below aperture B to allow the flange 12 to travel freely between the two positions of Fig. 1 and Fig. 2.

Support piece 13, a portion of the body means, has a hole 13a through which the bolt is movable. A compression spring 14 is held, between piece 13 and the flange 12, around the bolt, biasing the flange and bolt away from piece 13 in the "outward direction" of bolt movement. In Figs. 2 and 3 the spring is compressed, the bolt being unlocked; in Fig. 1 the spring has pushed the bolt out to the extended locked position, the movement between Fig. 2 and Fig. 1 being in said outward direction.

By comparing Fig. 1 with Fig. 3 it may be seen that to unlock the bolt from the first side one removes the padlock C, removes hasp 6 from staple 5, and by moving the hasp along slot 7 withdraws the bolt (its inward direction of movement), compressing spring 14 in the process; the collar portion 6b of the hasp engages the pin 10 to move the bolt.

A second support piece 15 of the body means has a bearing hole through which pin 16 passes rotatably, being held in place by a cotter pin and a washer. Pin 16 is a part of the catch 17, the detent region of whose cam surface is indicated at 18. The weight of the catch biases it against flange 12; when the bolt is withdrawn the detent region engages the flange to maintain the bolt in an unlocked position. The bolt may be relocked from the first side by raising (in aperture 20) external grasable control 19—allowing the flange to leave the detent region, so that the spring forces the bolt in its outward direction. From the second side, the bolt being unlocked (by handle 11) one can raise the catch to relock the bolt by swinging handle 11 up against internal control 21 as shown in dashed lines at 11a, 17a, 19a and 21a in Fig. 4. Or, internal control 21 may be raised manually.

In Fig. 6 an embodiment is shown in which internal control means 21' is somewhat longer than that used in the form of the other Figs. so as to permit ease of manual operation of the catch from the second side of the door; the catch is biased against the flange by a leaf spring 22 attached to the body shell 1'; and the external control 19' has a stud portion 23 which covers aperture 20' to prevent the entry of injurious materials into the bolt lock and which allows effective manual operation of control 19'. In this form of the bolt lock—although it is shown, like the preceding form, in a horizontal position—the device may be used with the bolt lying in a non-horizontal or effectively vertical position: the catch does not depend on gravity to bias it against the flange. The "outward" direction of the bolt movement could be either upward or, preferably, downward (as in use on a "dutch door").

The embodiment of the present invention specifically

described, illustrated and claimed herein is exemplary only, and is not intended to limit the scope of the present invention, which is intended to be interpreted in the light of the prior art and the appended claims only, with due consideration for the doctrine of equivalents.

I claim:

1. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means in said body means and passing through said first-end aperture in slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock; and having at an internal end a collar portion retainably slidable along said bolt means between two spaced positions relative to the longitudinal axis of said bolt means; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; catch means movably held by said body means and having a surface biased against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door.

2. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means in said body means and passing through said first-end aperture in slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means,

5 having an opening therein, at an external end, cooperable with said staple means to be locked thereto by said padlock, and having at an internal end a collar portion retainably slidable along said bolt means between two spaced positions relative to the longitudinal axis of said bolt means; handle means fixedly attached to said bolt means and projecting through said longitudinal side aperture and the corresponding aperture in the door to said second side to allow the forcible manual movement of said bolt means in said inward direction; catch means movably held by said body means and having a surface biased against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door.

3. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means in said body means and passing through said first-end aperture in slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably encompassingly slidable along said bolt means, said collar portion having an aperture therein, and said bolt means having a pin portion projecting therefrom cooperable with said collar aperture to abut against said collar portion at two longitudinally spaced opposing positions; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means movably held by said body means and having a surface biased against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door.

door, whereby said catch means may be disengaged from said flange means from either side of the door.

4. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means in said body means and passing through said first-end aperture in slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably encompassingly slidable along said bolt means, said collar portion having an aperture therein, and said bolt means having a pin portion projecting therefrom cooperable with said collar aperture to abut against said collar portion at two longitudinally spaced opposing positions; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means movably held by said body means and having a surface biased by the weight of the catch means against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door.

5. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means, and bolt support portions of said body means rotatably and longitudinally slidably holding said bolt means, which passes through said first-end aperture in rotatable and slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably encompassingly slidable along said bolt means, said collar portion having an aperture therein, and said bolt means having a pin portion projecting therefrom cooperable with said collar aperture to abut against said collar portion at two longitudinally spaced

ward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably encompassingly slidable along said bolt means, said collar portion having an aperture therein, and said bolt means having a pin portion projecting therefrom cooperable with said collar aperture to abut against said collar portion at two longitudinally spaced opposing positions; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means movably held by said body means and having a surface biased against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door; said second portion of the control means being operable by the manual swinging of said handle means, about the longitudinal axis of the bolt means, against said second portion.

6. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means, and bolt support portions of said body means rotatably and longitudinally slidably holding said bolt means, which passes through said first-end aperture in rotatable and slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably encompassingly slidable along said bolt means, said collar portion having an aperture therein, and said bolt means having a pin portion projecting therefrom cooperable with said collar aperture to abut against said collar portion at two longitudinally spaced

7
opposing positions; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means rotatably held by said body means and having a cam surface biased by the weight of the catch means against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door; said second portion of the control means being operable by the manual swinging of said handle means, about the longitudinal axis of the bolt means, against said second portion.

7. A bolt lock attachable to a door, cooperable with a padlock to lock said door to a jamb, and selectively unlockable from one side of said door and relockable from the other side of said door independently of said padlock, comprising: body means in the form of a longitudinal semicylindrical shell, open at its diametric plane, having first and second ends, having an aperture in said first end and being provided with portions by which it may be attached fixedly to a door with said diametric plane virtually in the plane of the surface of a first side of said door and adjacent to a corresponding aperture in said door; bolt means mounted longitudinally within said recess means, and bolt support portions of said body means rotatably and longitudinally slidably holding said bolt means, which passes through said first-end aperture in rotatable and slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably slidable along said bolt means between two spaced positions relative to the longitudinal axis of said bolt means; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means movably held by said body means and having a surface biased by the weight of the catch means against said flange means, a

portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being operable from the second side of the door, whereby said catch means may be disengaged from said flange means from either side of the door.

8. A bolt lock attachable to a door, cooperable with a padlock to lock said door to a jamb, and selectively unlockable from one side of said door and relockable from the other side of said door independently of said padlock, comprising: hollow body means having first and second ends, defining longitudinal recess means open at a longitudinal side aperture and at an aperture in said first end, and being attachable fixedly to a first side of a door, said side aperture being adjacent to a corresponding aperture in said door; bolt means mounted longitudinally within said recess means in said body means and passing through said first-end aperture in slidable engagement therewith; flange means projecting from said bolt means; spring means cooperable with said body means and said flange means to bias said bolt means in an outward direction, whereby a portion of said bolt may be made, in a locked position, to be maintained outwardly extended through said first-end aperture; staple means held in fixed relationship to said body means, cooperable with said padlock means to be interlocked therewith; side slot means defined by said body means, spaced from said side and end apertures; hasp means passing through said slot means, having an opening therein, at an external end, cooperable with said staple means to be locked thereto by said padlock, and having at an internal end a collar portion retainably slidable along said bolt means between two spaced positions relative to the longitudinal axis of said bolt means; whereby excess outward extension of the bolt means is prevented, unlocking retraction of the bolt means by the longitudinal motion of the hasp means in said side slot means is allowed, and unlocking retraction of the bolt means while the hasp means is immobilized is allowed, by the manual retraction of said bolt means from the second side of the door; handle means fixedly attached to said bolt means and projecting through said longitudinal side aperture and the corresponding aperture in the door to said second side to allow the forcible manual movement of said bolt means in said inward direction; catch means movably held by said body means, having a cam surface, and spring means biasing said surface against said flange means, a portion of said surface being engageable with the flange means to maintain said bolt means in a withdrawn unlocked position and selectively disengageable from the flange means to allow the motion of said bolt in its outward direction under the force of said spring means; control means attached to said catch means, and an aperture in said body means allowing the manual grasping of a first portion of said control means from the first side of the door, a second portion of said control means being extended through the aperture in the door and thus manually operable from the second side of the door, whereby said catch means may be disengaged from said flange means from either side of the door.
